[57] CLAIM

I claim the ornamental design for a hacksaw bow, as shown and described.

DESCRIPTION

FIG. 1 shows a right side view of a hacksaw bow embodying my new design;

FIG. 2 shows a left side view of the hacksaw bow, this view being identical to the right side view shown in FIG. 1;
FIG. 3 shows a top plan view of the hacksaw bow;
FIG. 4 shows a front elevational view of the hacksaw bow;
FIG. 5 shows a rear elevational view of the hacksaw bow;
and,

FIG. 6 shows a bottom plan view of the hacksaw bow.
